AIR SPEED ANNUNCIATOR

Application filed May 9, 1932. Serial No. 610,259.

This invention relates to an air speed annunciator for aircraft and the principal object of the same is to provide an apparatus for automatically notifying the occupants of an airplane, by audible means, of the upper and lower limits of a predetermined speed range.

Another object of the invention is to provide an audible air speed annunciator embodying a shutter-controlled siren in which the normal audible indication of the siren is destroyed or modified over any desired speed range by shutting off the air supply essential to the operation of the siren.

15 A further object of the invention is to provide control of a siren by means of dynamic air pressure created by relative motion between air and siren, the said air pressure acting on a spring-controlled vane thereby governing the position of a shutter and hence, the sound produced by the siren.

20 A still further object of the invention is to provide an audible air speed annunciator embodying a shutter-controlled siren having both a high and low speed adjustment enabling the device to operate over different speed ranges.

25 With the above in view, the invention consists, specifically, in the arrangement, construction, and combination of parts herein-after fully described and pointed out with reference to the accompanying drawings illustrating one embodiment of the invention, in which:—

30 Figure 1 is a front elevation of the device, partly broken away to show an initial setting of the shutter for a predetermined speed range;

35 Figure 2 is a similar view showing the position of the shutter after a predetermined movement from its initial position in Figure 1.

40 Figure 3 is a view showing the initial setting of the shutter for a different speed range;

45 Figure 4 is a central longitudinal sectional view of the device on an enlarged scale;

50 Figure 5 is an enlarged plan of the shutter assembly, and

Figure 6 is a cross section on line 6—6 of Figure 5.

The device embodies a casing composed of a siren shell 1 and a motor housing 2 connected by a tubular shaft housing 3. The shell 1 is provided with a series of circumferentially spaced, narrow, slots 4 and a cap or closure comprising spaced-apart members 5 and 6 having relatively aligned small central air inlet openings or ports 7 and 8. Upon entering the siren shell through the openings 7 and 8, the air impinges a conically shaped deflector 9 centrally positioned behind the port 7 in the cap and is thereby deflected through the peripheral openings or slots 4. The deflector is a part of the siren rotor 10 which also includes a plurality of radial vanes 11 which, by their rapid interruption of the current of air passing through the shell while the rotor is revolving, produce the musical tones of the siren. The frequency of the interruptions determines the pitch of the tone. The rotor is fixedly mounted on a motor-driven shaft 12, the motor 13 of which is enclosed in the motor housing 2 and electrically connected through the commutator 14, brushes 15, and leads 16 and 17 to a battery 18. The battery lead 16 includes the switch 19. It will be understood, however, that motor 13 may be replaced by any other source of power, such as an independent propeller, generator propeller, etc., without departing from the spirit of the invention.

It is a well known fact that a siren cannot operate in a vacuum. In putting this invention into practice, it is intended that the air supply to the rotor shall be substantially cut off at a certain predetermined speed which will in turn result in a marked difference in the intensity of tone generated by the siren. This is accomplished by means of a shutter composed of two superimposed leaves or segments 20 and 21 pivoted mounted, as at 22, between the spaced apart cap-members 5 and 6 for movement about a common axis. Each shutter segment is of a width slightly exceeding the diameter of siren port 7 in the cap so that when the shutter is closed, that is—when shutter seg-

ment 21 coincides with the shutter segment 20, the overall width of the shutter is just sufficient to enable the shutter, when disposed over the siren port 7, to fully cover the same and to substantially cut off the air supply to the rotor. By thus cutting off the air supply the normal audible indication of the siren is destroyed or muffled to such an extent that there is a marked difference in the intensity of tone generated by the siren. The shutter segment 20 is provided at the upper end with an integral wind-vane 23. A spring 24 is connected at one end to the vane 23 and at the other end to the low speed screw 25. Screw 25 is threadedly engaged in the bearing 26 of the low speed scale arm 27 mounted on the side of the siren shell 1. The head of the screw has an index 28 for properly locating the screw relative to the graduation of the low speed scale 29. Adjustment of the low speed screw 25 varies the angular position of the shutter and either increases or decreases the distance between the siren ports 7 and 8 and the leading edge A of shutter segment 20, according to the direction of the screw-adjustment. Hence, the adjustment of the screw and the consequent positioning of the shutter segment 20 relative to the siren ports 7 and 8 determines the low air speed necessary to cause the shutter to cover the siren ports. The overall width of the shutter determines the high air speed necessary to move the shutter past the siren ports against the action of spring 24. The effective overall width of the shutter may be varied by the spreading or opening of the shutter segments 20 and 21, the maximum overall width preferably being equal to the combined width of the respective shutters. The shutter segments are held to any desired overall widths within given limits by a binding nut 30 on the outer end of a screw 31 carried by shutter segment 20 and working in an arcuate slot 32 in shutter segment 21. This latter segment is provided with a high speed scale 33 having a limited number of radial graduations or index lines 34 representing predetermined high speed limits. Encircling the base of vane 23 of shutter segment 20 is an adjustable high speed scale 35 in the form of an endless ribbon, the graduations or index lines 36 of which correspond to the radial indexes 34 of the high speed scale 33, being in effect merely vertical prolongations of the radial indexes. The adjustable ribbon scale is held in any position to which adjusted by means of a lock screw 37. The shutter segment 20 is also provided, above the adjustable ribbon or high speed scale 35, with a fixed low speed scale 38 corresponding to the low speed scale 29. Whenever an adjustment of the low speed screw 25 is made, the width of the shutter must obviously be varied if the

same high speed limit is to be maintained. Scales 33 and 35 are used, as hereinafter explained, in conjunction with scale 38 in determining the proper adjustment of the shutter segments whenever there is any change in the low speed setting of the shutter.

In the following description of the operation of the device, it is assumed that the same is mounted on an airplane with the axis of rotor 10 parallel to the line of flight with the vane 23 presented to the air stream at such an angle that the latter tends to move the vane, and hence the shutter, in a clockwise direction about its pivot 22 against the tension of spring 24. The axis of the rotor need not, necessarily, be parallel to the line of flight but in any event must be so positioned that the vane 23 is subjected to dynamic air pressure, such as created by relative motion between air and siren. For convenience of description, a portion of the arc through which the shutter moves is shown, in Fig. 5, marked off into segments of 10 degrees each. The diameter of opening 7, as well as the effective width of each shutter segment 20 and 21, is assumed to be the equivalent of or equal to 20 degrees and for present purposes the scale of the device is considered to be: 1 degree = 2 miles per hour. In the position of the parts, as illustrated in Figure 5, the shutter movements required to produce low and high speed warnings have been designated by the letters "X" and "Y." Let it be assumed that the annunciator is to be set to operate at speed range having a low speed of 40 M.P.H. and a high speed of 120 M.P.H. The low speed screw 25 is adjusted as shown in Fig. 1 until the index 28 is opposite the graduation of the scale 29 corresponding to 40 miles per hour. This adjustment of the screw positions shutter segment 20 with its leading edge A spaced from the farthest side of opening 7 a distance "X" corresponding to 20 degrees or 40 miles per hour, in accordance with the scale of the apparatus. The dynamic air pressure created by relative motion between air and siren, acting on the spring-controlled vane 23, moves the shutter segment 20 toward the siren port 7 proportionably to the rate of increase in the air speed. Hence, when the air speed reaches 40 miles per hour, the shutter segment 20 shall have been moved the distance "X" and will cover the siren port, resulting in a marked difference in the intensity of the tone generated by the siren. The width of the shutter determines the high air speed necessary to again open the siren port by further deflection of the spring 24, thereby again making the siren normally operative. Since it is desired that the siren be normally operative at a high air speed of 120 miles per hour, the ribbon scale 36 is ad-

justed on shutter segment 20 until its particular scale graduation or index-line designated by the number "120" is in line with the scale mark "40" of low speed scale 38. 5 The shutter segment 21 is adjusted in a counter clockwise direction until the radial index line marked "120" is lined up with the index lines "120" and "40" of the scales 36 and 38, respectively. Index lines 10 34, 35 and 39 serve as guides in properly lining up the various scale marks. When properly adjusted, the leading edge of the shutter segment 21 will be adjacent the trailing edge of shutter segment 20, as indicated 15 at B, so that the shutter is at its maximum overall width, or a distance "y" corresponding to 40 degrees. This places the trailing edge of shutter segment 21 a distance "Z", corresponding to 60 degrees or 120 miles 20 per hour, from the farthest side of siren port 7. Hence, the trailing edge "C" of the shutter will not be moved past the opening 7 as shown in Fig. 2 until the air speed increases from 40 to 120 miles per hour. 25 Should it be desired to reset the device for operation at a different low speed limit while maintaining the original high speed limit, it is necessary to make a corresponding adjustment of the value "Z." For example, to change the low speed limit from 40 miles per hour to 50 miles per hour, leaving the high speed limit at its original figure "120", the screw 25 is first adjusted to the position corresponding to 50 miles per hour. 30 The resultant movement of the shutter places the leading edge A a distance "Z" of 25 degrees, corresponding to 50 miles per hour, from the farthest side of opening 7 as shown in Fig. 3. The trailing edge C, however, 35 will be a distance "Z" of 65 degrees, corresponding to 130 miles per hour whereas only a high speed limit of 120 miles per hour is desired. Hence, in order that the high speed limit will remain at 120 miles per hour, the 40 distance "Z" must obviously be reduced. This is accomplished by reducing the overall width of the shutter. A convenient way of doing this is to shift the ribbon scale 35 until the scale mark "120" is aligned with the scale 45 mark "50" of the low speed shutter scale 38. The shutter segment 21 is adjusted relative to the segment 20 and in a clockwise direction until the radial scale mark "120" is properly lined up with the previously 50 aligned scale marks "120" and "50" of the scales 35 and 38, respectively. The distance "z" will then have a value of 60 degrees or 120 miles per hour. For other speed ranges, the shutter segments shall be adjusted accordingly.

It will be observed that the foregoing is merely illustrative of a single embodiment of the invention and that in the practical application of the same, various changes, 55 modification, and alterations in the scale and

design of the annunciator may be required to meet conditions of use. The invention is not to be understood, therefore, as being limited to the exact construction herein set forth but rather susceptible to all such changes and modifications as fall within the limits and scope of the appended claims. 70

I claim:

1. The combination with a siren of means responsive to dynamic air pressure created by relative motion between air and siren for cutting off the air supply to the siren. 75

2. The combination with a shutter controlled siren of shutter-actuating means responsive to dynamic air pressure created by relative motion of air and siren for governing the position of the shutter. 80

3. The combination with a shutter-controlled siren of a spring-tensioned wind vane on the shutter and responsive to dynamic air pressure created by relative motion of air and siren for governing the position of the shutter and hence the sound produced by the siren. 85

4. An air speed annunciator including a siren, means for causing cessation of the normal audible indication of the siren immediately above a predetermined air speed, and means for restoring normal audible indication above a predetermined higher air speed. 90

5. An air speed annunciator including a siren and means for shutting off the fluid supply essential to the operation of the siren over a predetermined speed range, said means having a high and a low speed adjustment. 100

6. A device for indicating the upper and lower limits of a predetermined speed range including a siren and means responsive to dynamic air pressure for substantially cutting off the air supply to the siren over the predetermined speed range to produce a marked difference in the intensity of tone generated by the siren. 105

7. A device for indicating the upper and lower limits of a predetermined speed range including a siren and means responsive to dynamic air pressure for cutting off the air supply to the siren over the predetermined speed range, said means having both a high and a low speed adjustment enabling the device to operate over different speed ranges. 115

8. An audible air speed annunciator including the combination with a moving vehicle of means operated by dynamic air pressure created by relative motion between air and vehicle for automatically notifying the occupants of the vehicle by audible indication of the upper and lower limits of a predetermined speed range. 120

9. An air speed annunciator including a siren having an air-intake port, a shutter for closing said air-intake port, a tension spring connected with said shutter, and a 130

wind vane on said shutter responsive to air pressure for moving the shutter against the action of the spring.

10. An air speed annunciator including a siren having an air-intake port, a shutter movable across said port for alternately closing and opening same, a tensionable connection between the shutter and the siren adjustable for varying the position of the shutter laterally of the said air-intake port, and a wind vane on said shutter responsive to air pressure for moving the shutter against the tension of the spring.

11. An air speed annunciator including a siren having an air-inlet, a shutter of variable width mounted on said siren for movement across said air-inlet to alternately close and open the same, a tensionable connection between the shutter and the siren adjustable for varying the position of the shutter laterally of the air-inlet, and a wind vane on said shutter responsive to air pressure for moving the shutter against the action of the spring.

25. 12. An air speed annunciator including a siren having an air-intake port, a multi-segmental shutter pivotally mounted on the siren and having the shutter segments relatively adjustable for varying the overall width of the shutter, means on the shutter responsive to dynamic air pressure for moving the shutter across the air-intake port to alternately cut off and restore the air supply essential to the operation of the siren, adjustable shutter-positioning means operable for properly positioning the shutter relative to the air-intake port so that the air supply will be cut off immediately above the lower limit of a predetermined air speed range, and means on said adjustable shutter segments correlated with the shutter-positioning means for determining the width of shutter required for the higher limit of the said predetermined speed range.

45. 13. An air speed annunciator including a siren shell having a series of circumferentially spaced air-exhaust slots, a closure for said shell comprising spaced inner and outer members having relatively aligned and cen-

tered air-inlet openings respectively, a motor-driven siren rotor enclosed within said shell, a multi-segmental shutter pivotally mounted on the said closure between the inner and outer members thereof and having the shutter segments relatively adjustable for varying the overall width of the shutter a wind vane on one of the shutter segments responsive to dynamic air pressure for moving said shutter across the said air-inlet openings to alternately cut off and restore the air supply essential to the operation of the siren, a scale arm on said shell having a low speed scale, an adjusting screw threadedly engaged in said arm and having an index for properly locating the screw relative to the graduations of the low speed scale, a spring connected at one end to the said screw and at the other end to the said vane, and scale means on the said adjustable shutter segments correlated with the low speed scale of the said shell for determining the width of shutter required for any predetermined speed range.

14. An audible air speed annunciator including a siren and means responsive to air pressure created by relative motion of air and siren for rendering said siren inoperative between lower and upper limits of a given range.

15. A speed indicator comprising the combination with a moving body of means carried thereby and responsive to relative motion between the body and the medium through which it moves for indicating by perceptible action the upper and lower limits of a predetermined speed range.

16. A speed indicator comprising the combination with a moving body, of signalling means carried thereby and responsive to relative motion between the body and the medium through which it moves for indicating by perceptible action the upper and lower limits of a given speed range, and a manually settable control device for the signalling means operable to vary the signally-active range of the device.

In testimony whereof I affix my signature.
JESSE E. ESHBAUGH.
